(57) **CLAIM**

The ornamental design for an anti-theft security device for use with bottles, as shown and described.

DESCRIPTION

FIG. 1 is a front elevational view of an anti-theft security device for use with bottles showing my new design;
FIG. 2 is a side elevational view, the opposite side view being a mirror image thereof;
FIG. 3 is a top plan view thereof;
FIG. 4 is a bottom plan view thereof;
FIG. 5 is a rear elevational view thereof; and,
FIG. 6 is a perspective view thereof, in an open condition.
The broken lines are for illustrative purpose only and form no part of the claimed design.
